UNITED STATES PATENT OFFICE.

EDWARD R. NORMAN, OF CHICAGO, ILLINOIS.

PACKING RING.

Original application filed June 4, 1917, Serial No. 172,604. Divided and this application filed November 28, 1917. Serial No. 204,310.

To all whom it may concern:

Be it known that I, EDWARD R. NORMAN, a citizen of the United States, residing at Chicago, in the county of Cook and State 5 of Illinois, have invented certain new and useful Improvements in Packing Rings, of which the following is a specification, reference being had therein to the accompanying drawing.

10 My invention relates to packing rings, and consists in the matters hereinafter described and then pointed out in the claims, this application being a division of my prior application filed June 4, 1917, and bearing Serial 15 Number 172,604, series of 1915, patented Jan. 28, 1919, No. 1,292,633.

In the accompanying drawings,

Fig. 1 is a side view of the ring with the joint closed;

20 Fig. 2 is a detail plan view with the joint closed;

Fig. 3 is a detail perspective view with the joint closed;

25 Fig. 4 is a detail plan view of the ring with its joint open to better show the construction of its parts;

Fig. 5 is a similar side view;

30 Fig. 6 is a detail side view of the ring showing the joint extended but forming a seal when the ring is expanded, and

Fig. 7 is a similar plan view.

The ring R is made from an oval blank which may be individually cast or cut from a pot-casting, with the scale of harder metal 35 resulting from the chilling of the inner and outer surfaces removed from its outer surface or periphery but retained on its inner surface, the sides of the blank being rough ground to the desired width of the ring.

40 The blank is larger than the ring desired and is suitably divided, and the ends are cut or milled to form the joint by removing sufficient material so that the finished ring is circular when the joint is closed, preferably by the process which forms part of 45 the subject-matter of my above designated application.

The opposite ends of the ring are formed with laterally overlapping tongues 10 and 50 11 disposed on the opposite sides of the median line of the width of the ring as shown in Figs. 2 and 7, the removal of the metal to form the tongues providing corresponding recesses which are on opposite sides 55 of said median line and are respectively disposed in the line of the tongues 10 and

11. Each tongue is composed of a body *w* and *w'*, respectively, of the same thickness as the ring itself, and a radially reduced end portion formed by cutting away its 60 inner face, and each recess is provided at its base with a shoulder 12 and 13, respectively, each adapted to co-operate with the opposite reduced tongue-end. Each tongue and its opposed shoulder have opposite bearing 65 or seating surfaces which are curved on a radius greater than but concentric with the radius of the blank at its point of division so that when the joint is closed the ring is circular and the opposite seats are extended 70 or prolonged in the circumferential line of the finished ring concentric with its curvature to close without friction or binding and form a circumferentially elongated seal having a greater area or extent than the 75 mere "line" or "edge" seal now generally used. The tongue 10 is provided on its inner face with a bearing or seating surface *x*⁸ formed by cutting away a portion of its inner surface to a depth preferably equal 80 to about half the thickness of the ring, the base of the seat being rounded as at *z*³ and the tip of the tongue being also rounded as at *y*³; the opposite shoulder 12 is provided with a co-operating seat *x*² formed with a 85 rounded base *z*² to receive the tip *y*³ and with a rounded tip *y*² to fit the base *z*³ of the seat *x*⁸. The tongue 11 is similarly provided on its inner face with a bearing or seating surface *x'* having a rounded tip 90 *y'* and a rounded base *z'*, and the opposite shoulder 13 is similarly provided with a co-operating seat *x*' having a rounded base *z* to receive the tip *y'* and a rounded tip *y* to fit the base *z'* of the seat *x*'. The parts 95 are so formed that when the opposing seats are engaged the peripheries of the tongues are flush with each other and on the same circumference as the body of the ring, and preferably each tongue and shoulder is equal 100 to half the thickness of the ring. When the ring is closed in use the tongues 10 and 11 overlap as shown in Figs. 2 and 6, each projecting into an opposite recess, and the opposite pairs of seating surfaces *x*, *x'* and 105 *x*², *x*³ co-operate on opposite sides of the median line and on opposite sides of the base portions of the tongues, and as the seating surfaces are elongated or prolonged in the direction of the plane of the ring they form 110 a circumferentially extended seal. The bodies of the tongues of the same thickness

as the ring itself are of such length circumferentially that they overlap when the joint is extended by the expansion of the ring, and the co-acting seats on the tongues 5 and shoulders are similarly circumferentially elongated and are concentric with the curvature of the ring so that they remain in extended contact whether the ring is entirely closed as when the contour of the containing cylinder walls hold it in this position as in Figs. 1 and 3, or is only partly closed 10 as when for example it expands to fit an oversized or a worn cylinder as in Figs. 6 and 7. In short, the joint is provided with 15 circumferentially co-operative seats which retain extended contact when the diameter of the ring is increased and permits the ring to retain its circular form at all times without affecting its sealing capacity. Also, the 20 tongues are external or on the outer surface of the ring, and consequently each inner shoulder interlocks with its tongue to resist the pressure on either side of the joint and neither portion of the joint can open radially, while at the same time the tongues are 25 not confined by the opposite ends of the ring but can freely expand or move outwardly when the ring is opened to fit over the associated piston, and then freely reseat on the 30 shoulders without any hand-fitting and without abutting against the shoulders when the ring is compressed into the piston groove by

insertion in the associated cylinder, so that the liability of the tongues to break off, which is an objection where the tongues are 35 inside the ring, is obviated by my invention. The shoulders on the inner surface of the ring are integral along one side with the corresponding tongues, and so are reinforced against breakage. 40

I claim:

1. A transversely split packing ring having on each of its ends an outer projection and an inner shoulder, the projection on one end fitting over and contacting with the shoulder on the opposite end and the projections and shoulders all extending transversely of the ring to a common circumferential plane. 50
2. A transversely split packing ring having on each of its ends an outer projection and an inner shoulder, the projection on one end fitting over and contacting with the shoulder on the opposite end and the projections and shoulders all extending transversely of the ring to the median circumferential plane of the ring. 55

In testimony whereof I affix my signature in presence of two witnesses.

EDWARD R. NORMAN
